UNITED STATES PATENT OFFICE.

CHARLES S. TOBIAS, OF CINCINNATI, OHIO.

CAP.

SPECIFICATION forming part of Letters Patent No. 723,946, dated March 31, 1903.

Application filed July 19, 1902. Serial No. 116,162. (No model.)

To all whom it may concern:

Be it known that I, CHARLES S. TOBIAS, a citizen of the United States, residing at Cincinnati, in the county of Hamilton and State 5 of Ohio, have invented certain new and useful Improvements in Caps, of which the following is a specification.

This invention relates to improvements in caps, and more especially to that class of caps 10 that are provided with a portion that can be folded down over the ears, so as to protect them and be retained by the lobes of the ears without danger of removal by storms or otherwise, the protecting portion being adapted to 15 be folded inside or outside of the body of the cap, as desired; and for this purpose the invention consists of a cap which is provided at its sides and rear with a folding portion that may be extended downwardly over the 20 ears and back of the head, said downwardly-extending portion being provided at its inner front part with auxiliary segmental pieces adapted to fit under the front portion of the lobes of the ears, and thereby serve to retain 25 the cap on the head in addition to the fit of the body of the cap to the head; and the invention consists, further, of certain additional details of construction, which will be more fully described hereinafter and finally pointed out 30 in the claims.

In the accompanying drawings, Figures 1 and 2 are perspective views of my improved cap, showing the folding portions folded, respectively, inwardly into the body of the cap 35 and over the outside of the same. Figs. 3 and 4 are vertical transverse sections, respectively on lines 3 3, Fig. 1, and 4 4, Fig. 2. Fig. 5 is a perspective view of the cap, showing it in position on the head for protecting 40 the ears; and Fig. 6 is a detail section on line 6 6, Fig. 5.

Referring to the drawings, A represents a cap made of cloth or other suitable material and in the general style of a golf-cap. To 45 the lower rear part of the cap A is attached a folding portion B, which can be folded inside or outside of the cap when it is not desired for use, or it can be turned down over the ears, so as to protect the same in cold or 50 stormy weather.

To the curved front parts of the folding portion B are attached auxiliary portions C, approximately of segmental shape, which form pockets with the portions B for the front

portions of the lobes of the ears and which 55 serve also by engaging under the lobes as retainers for holding the cap firmly on the head without requiring the tying of the same.

The folding portion B, with its under lobe-covering portions C, is either folded inwardly 60 into the body of the cap, as shown in Figs. 1 and 3, or it may be arranged on the outside of the same, as shown in Figs. 2 and 4, in which case the ends of the folding portion are tied by means of the tie-bands b, said bands 65 being tied together across the body of the cap, and tied neatly into a bow, which, together with the exterior folding portion, form ornamental features of the cap. When the folding portion is folded into the inside of the cap, the 70 fastening-bands may be stored away in the pockets formed by the ear-lobe-covering portion as shown by dotted lines in Fig. 1, and may be used in very stormy weather for being tied below the chin, so as to hold the cap, in addition to the ear-lobe-covering portions, firmly 75 on the head of the wearer.

My improved cap has the object that the cap not only protects the ears, but also affords a satisfactory headwear that is retained firmly 80 on the head in windy weather and that presents a pleasing appearance.

Having thus described my invention, I claim as new and desire to secure by Letters Patent—

85

1. A cap provided with a folding portion extending along the sides and rear part of the same, said folding portion being provided at its inner front ends with auxiliary segmental pieces forming ear-lobe pockets, substantially 90 as set forth.

2. A cap provided along the sides and rear of the same with a folding portion adapted to be folded inside or outside of the cap, auxiliary ear-lobe-engaging portions at the front 95 ends of said folding portion, and fastening-bands attached to the front ends of said folding portion and adapted to be stored away in the pockets formed by the ear-lobe segmental portions or to be tied together across the body 100 of the cap, substantially as set forth.

In testimony that I claim the foregoing as my invention I have signed my name in presence of two subscribing witnesses.

CHARLES S. TOBIAS.
